HENRY J. KIMMAN, OF CLEVELAND, OHIO, ASSIGNOR TO CHICAGO PNEUMATIC TOOL COMPANY, OF CHICAGO, ILLINOIS, A CORPORATION OF NEW JERSEY.

THROTTLE-VALVE FOR FLUID-PRESSURE TOOLS.

1,350,102.

Specification of Letters Patent.

Patented Aug. 17, 1920.

Application filed August 21, 1919. Serial No. 318,936.

To all whom it may concern:

Be it known that I, HENRY J. KIMMAN, a citizen of the United States, residing at Cleveland, in the county of Cuyahoga and 5 State of Ohio, have invented certain new and useful Improvements in Throttle-Valves for Fluid-Pressure Tools, of which the following is a specification.

My invention relates to a throttle valve 10 for a tool operated by fluid pressure such as pneumatic drills, hammers, etc. The object of my invention is to provide a throttle valve having features of safety whereby the throttle cannot be opened accidentally but only 15 intentionally when required for use. Laws of certain of the States require that tools of this character shall be made safe so as to protect the operator or workman from injury, and the throttle valve here produced 20 by me is made to comply with such laws.

In the drawings Figure 1 is a top plan view of the fluid pressure or air conduit containing my safety throttle valve; Fig. 2 a side elevation thereof; Fig. 3 a view similar to Fig. 1 but with the oscillating shell removed to expose the parts within; Fig. 4 a central section on the line 4—4 of Fig. 1; Fig. 5 an elevation of the throttle valve removed; Fig. 6 a section on the line 6—6 of 25 Fig. 4; and Fig. 7 a detail view showing a certain condition of the trigger with respect to the valve slide.

My invention may partake of different embodiments without departing from the 35 spirit of my invention and may moreover partake of different forms according to the particular use or tool to which it may be applied. In the present instance I have shown my invention embodied in a handle 40 or conduit as applied to a drill such as a pneumatic drill, and for the sake of brevity and clearness of description, my invention will be described in connection therewith. Moreover, my invention while more particularly intended for use in connection with 45 air drills or air tools in general it will be understood that its use is not limited thereto. However, it will be understood that when I refer to the use of air that my invention is not limited to tools employing such fluid pressure medium.

My throttle valve 1 is in the present instance arranged in a passage 2 for fluid pressure which will be hereinafter referred 50 to as air, which passage extends centrally

through the conduit 3. This conduit is adapted in the present instance to be secured at its left-hand end to the tool proper such as a drill and to receive the air under pressure from a suitable source through the 60 nipple connection 4 at the right-hand end of the conduit.

The passage 2 is enlarged or counterbored at its rearward or right-hand end so as to form a valve chamber 5 within which is by 65 preference located a bushing 6. The throttle valve 1 is adapted to slide within this bushing and to seat upon the rearward end thereof. The throttle valve consists of a cylindrical or tubular body portion which is cut 70 away and also hollow as shown in Figs. 4, 5 and 6 and is provided with a head 7 which forms the valve proper and which is adapted to seat upon the seat 8 formed at the rearward end of the valve bushing. The valve 75 is normally held seated in suitable manner as by means of the coiled spring 9 bearing at one end against the nipple 4 and at the other end upon the valve head 7.

The throttle valve is provided with means 80 whereby it may be operated which as shown consists of a stud 10 screwing into the body or guide portion of the valve and passing outwardly through a longitudinal slot 11 extending through both the bushing 6 and 85 the reduced side of the conduit 3.

The conduit 3 at a point radially of the valve chamber is longitudinally slotted to form the recess 12 within which is adapted to reciprocate a valve slide 13 having a 90 hole to receive the head of the stud 10. When the slide 13 is reciprocated in a right-hand direction by the means hereinafter described it will move the throttle valve in the same direction against the tension of the 95 spring 9 and thereby open the passage through the conduit and permit the air to pass to the tool.

This valve slide 13 consists of a rectangular stem portion fitting within the recess 12 100 and a head portion 14 at the forward or left-hand end which head portion is adapted to move in the circumferential recess 15 in the conduit 3. This head 14 has its forward edge formed oblique, that is inclined to the 105 central longitudinal axis of the entire slide.

The operating means for the slide consists of an oscillating shell 16 and a hand or finger operated trigger 17 pivoted at 18 in said shell. By preference this shell is made 110

in two separate sheet metal sections which are held together in detachable manner by the split rings 19 and 20 engaging circumferential grooves at the ends of these sections, which are themselves held in place against longitudinal displacement by the shoulder 21 formed in the conduit and also by the shoulder 22 formed by the forward end of the nipple 4. This shell is adapted 10 to be oscillated within fixed limits, to which end one of the sections thereof is expanded outwardly to form a groove 23 which is coincident with a plane passing transversely through such shell and conduit. A suitable 15 projection 24 is secured to or formed in one side of the conduit so as to project within the groove 23, whereby the contact of the ends of such groove with such projection 24 will determine the limits of oscillation of 20 the shell and the trigger.

The trigger consists of an arm or plate pivoted at 18 and extended through a slot 25 formed at one of the meeting edges of the two sections of the shell. The trigger is 25 provided on its lower edge with an inwardly extending finger 26 normally positioned in the space within the recess 15 immediately in advance of the inclined end or face of the slide 13 as shown in Fig. 3.

30 Describing the operation and starting with the parts in the normal position shown in Fig. 4 for instance, when it is desired to admit air to the tool, the operator by pressure of his hand or fingers forces the trigger 35 inwardly so that the finger 26 will be positioned in front of the slide 13 and thereupon moves the shell and trigger in a clockwise direction with the result that by cam action between the finger 26 and end of the 40 head 14 the slide 13 will be moved longitudinally to the right and the throttle valve will be thereby opened. The valve remains open so long as the operator maintains this pressure and position of the trigger, but when 45 the same is removed the spring 9 will restore the parts to the normal position and shut off the supply of air.

As shown in Fig. 4 the side or face of the finger 26 which contacts the inclined or cam face of the head 14 is inclined or beveled with the result that in the event that the shell should be oscillated accidentally or unintentionally without any pressure being exerted upon the trigger, such finger 26 will 55 ride upwardly of the head 14 and move the trigger radially and thereby take the position upon the top or outer surface of the head 14 as shown in Fig. 7. Thus the opening of the throttle valve is dependent upon 60 two factors, first the pressure of the operator upon the trigger so as to keep the finger 26 always in advance of the cam face of the head 14, and second the oscillation of the shell and finger. It is only by the combined 65 action of these two factors that the throttle

valve is opened and consequently accidental operation cannot occur because an outside influence would affect only one of the factors at a time and not both together. The throttle valve is therefore of the safety type 70 and is reliable and efficient for this purpose. It is moreover very simple in construction and can be readily assembled and disassembled for any desired purpose.

I claim:

1. The combination of a throttle valve and means for operating the same including a member operatively connected with the valve, and a device having a rotary and a radial movement and adapted to be pressed 80 into operative relationship with said member and then when rotated to actuate the latter to cause operation of the throttle valve.

2. The combination of a throttle valve 85 and means for operating the same including a member operatively connected with the valve, and a pivoted lever having a rotary movement bodily and adapted to be pressed into operative relationship with said member 90 and then when rotated to actuate the latter to cause operation of the throttle valve.

3. The combination of a throttle valve and means for operating the same including a 95 valve slide operatively connected with the valve and having a cam surface and a lever which is mounted to rotate bodily and which has a portion adapted to coöperate with said cam surface to move the slide longitudinally 100 when in contact therewith and when rotated.

4. The combination of a throttle valve and means for operating the same including a valve slide operatively connected with the valve and having a cam surface and a rotarily mounted hand-operated lever having a projection provided with a cam surface adapted to coöperate with the other cam surface to move the slide longitudinally, said surfaces being formed to cause the lever 110 when rotated, to ride out of engagement with the slide unless held pressed into engagement therewith.

5. The combination of a throttle valve, and means for operating the same including 115 a valve slide operatively connected with the valve and consisting of a longitudinally sliding stem portion and a head portion having a cam edge, and a hand-operated bodily rotatable pivoted lever provided with a finger 120 having a cam edge adapted to coöperate with the other cam edge and to move the slide longitudinally when the finger is held pressed into engagement with the slide.

6. The combination with a tubular conduit 125 having a fluid pressure passage, a throttle valve therein to govern such passage, a valve slide mounted to slide on the conduit and operatively connected with the throttle valve, a rotatable member mounted to oscil- 130

late by hand on the conduit, and a hand operated lever pivoted on said member and having a portion adapted to coöperate with the slide and move the same whenever the member is oscillated and the lever held pressed into engagement with the slide.

7. The combination with a tubular conduit having a fluid pressure passage, a throttle valve therein to govern such passage, a valve slide mounted to slide on the conduit and operatively connected with the throttle valve, a shell mounted to oscillate by hand on the conduit, and a hand operated lever pivoted on said shell and having a portion adapted to coöperate with the slide and move the same whenever the shell is oscillated and the lever held pressed into engagement with the slide.

8. The combination with a tubular conduit having a fluid pressure passage, a throttle valve therein to govern such passage, a valve slide mounted to slide on the conduit and operatively connected with the throttle valve, a shell mounted to oscillate by hand on the conduit, and a hand operated lever pivoted on said shell and having a portion adapted to coöperate with the slide and move the same whenever the shell is oscillated and the lever held pressed into engagement with the slide.

9. The combination with a tubular conduit having a fluid pressure passage, a throttle valve therein to govern such passage, a valve slide mounted to slide on the conduit and operatively connected with the throttle valve, a shell mounted to oscillate by hand on the conduit, and a hand operated lever pivoted on said shell and having a portion adapted to coöperate with the slide and move the same whenever the shell is oscillated and the lever held pressed into engagement with the slide, said shell being made in two detachable parts having at one set of the meeting edges a slot to receive the lever, and detachable means for holding the sections together.

10. The combination with a tubular conduit having a fluid pressure passage, a throttle valve therein to govern such passage, a valve slide mounted to slide on the conduit and operatively connected with the throttle valve, a shell mounted to oscillate by hand on the conduit, and a hand operated lever pivoted on said shell and having a portion adapted to coöperate with the slide and move the same whenever the shell is oscillated and the lever held pressed into engagement with the slide, and means for limiting the oscillating movement of such shell.

11. The combination with a tubular conduit having a fluid pressure passage, a throttle valve therein to govern such passage, a valve slide mounted to slide on the conduit and operatively connected with the throttle valve, a rotatable member mounted to oscillate by hand on the conduit, and a hand operated lever pivoted on said shell and having a portion adapted to coöperate with the slide and move the same whenever the shell is oscillated and the lever held pressed into engagement with the slide, and means for limiting the oscillating movement of such shell.

12. The combination with a tubular conduit having a fluid pressure passage, a throttle valve therein to govern such passage, a valve slide mounted to slide on the conduit and operatively connected with the throttle valve, a shell mounted to oscillate by hand on the conduit, and a hand operated lever pivoted on said shell and having a portion adapted to coöperate with the slide and move the same whenever the shell is oscillated and the lever held pressed into engagement with the slide, and means for limiting the oscillating movement of such shell comprising a projection on the conduit and a coöperating groove on the inner surface of the shell.

13. The combination of a throttle valve and means for operating the same including a member operatively connected with the valve, said member and device coacting to cause said device when rotated to ride out of engagement with such member unless pressed into engagement therewith.

HENRY J. KIMMAN.
